UNITED STATES PATENT OFFICE.

JOHN ANTONELLI, OF CHICAGO, ILLINOIS.

GARMENT.

1,276,854.

Specification of Letters Patent. Patented Aug. 27, 1918.

Application filed August 10, 1914. Serial No. 855,979.

To all whom it may concern:

Be it known that I, JOHN ANTONELLI, a subject of the King of Italy, and a resident of Chicago, in the county of Cook and State 5 of Illinois, have invented certain new and useful Improvements in Garments, of which the following is a clear, full, and exact specification, reference being had to the drawings forming a part hereof.

10 My invention relates generally to the garment class, and has reference more particularly to an improved body capable of being accurately fitted to a round shouldered person.

15 Among the principal objects of my invention is to produce a coat adapted for quick and accurate fitting to a round shouldered person and in such a manner as to readily overcome any flaring out of the bottom back 20 portion of the coat and thereby obtain a good fit over the shoulders and hips. Another object of my invention is the provision of a novel arrangement of coat sections and joining seams whereby to eliminate the customary operation of ripping off the collar and altering the shoulder seams, which latter requires a nicety of fitting obviated by 25 my arrangement.

These, together with such other objects as 30 may hereinafter appear, or are incident to my invention, I attain by means of a construction illustrated in preferred form in the accompanying drawings, wherein:

Figure 1 is a perspective view of my improved garment;

Fig. 2 is a back view of the same, and

Fig. 3 represents a side view of Fig. 2.

Similar letters of reference indicate corresponding parts in the several figures.

40 Referring to the drawings, A indicates the coat body generally, composed desirably of the back sections 10, shoulder sections 11, side sections 12, collar 13, and front sections 14. If considered preferable the back sections and side sections may be made in one 45 piece, though I prefer to use the sectional form as shown.

Extending between the arm holes 15 and joining the shoulder and back sections is a 50 transverse seam *a* desirably inclining downwardly from the arm holes to the vertical seam *b*, the seam *a* as shown being substantially of a V shape.

As is well known, it is customary when 55 fitting the usual coat to rip off the collar, and then the shoulder seams, as *b'*, are sub-

sequently let out to accommodate any stoop acquired by the wearer. This, however, is an operation requiring a high degree of skill, occupying much time in order to obtain a 60 good fit and to eliminate any lowering of the back section or sections relative the bottom edge of the front sections, or flaring away from the hips. In adapting my coat to the desired contour of the shoulder, the 65 necessary adjustment is obtained through the seam *a* which permits the material to be taken in or let out to the extent required, the degree of adjustment obtained being ordinarily greater adjacent the seam *b* than in 70 the vicinity of the arm holes, as will be readily understood. Any subsequent flaring out of the back sections in a direction away from the hips of the wearer is entirely overcome by providing the adjustable side seams 75 *c*, which join the front sections 14 and the side sections 12, the latter in turn being joined with the back sections 10 by the seam *d*, as in the preferred arrangement.

Referring now more particularly to Fig. 3, 80 it will be seen that the front section 14 extends rearwardly from within the collar 13 to a point substantially forward of and beneath the arm hole 15 and thence inclines forwardly and downwardly to the bottom 85 edge of the coat. This, of course, defines the contour of the seam *c* as shown in the preferred construction, and its adjustment to take in the flare of the back bottom portion of the coat is obtainable in its lower inclined 90 portion, the upper portion *d'* of which is capable of adjustment independently of the seam *c* to correct the hang of the coat at the front. In this event, the collar is only ripped up to the top end of the seam *d'* where 95 material may be taken in or let out to respectively lower or raise the collar, and need not be removed from the coat. A pocket 16 is formed in the front section 14 and has its opening conveniently located in the seam *d'*, 100 that angular portion of the seam *c* rearwardly of the pocket 16 being adjustable to permit the making of the coat front larger, as, for instance, to accommodate a stout person, without ripping off the sleeve 105 and obviating creasing of the material about the arm-hole.

From the foregoing, it will be apparent that the seam *a* permits the material to be quickly and accurately fitted to the contour 110 of shoulders, and adjustment of the seam *c* readily compensates for any inaccuracy in the

"hang" of the coat at the front or back, and since none of these operations require much skill or expenditure of time and labor a cheaper and better product is thus obtained. The essential elements and features of the article, together with its simplicity and other advantages thereof, will be readily apparent to those skilled in the art.

I do not intend to restrict myself to the precise arrangement of the parts, as it is obvious that variations thereof may be made without in any way departing from the spirit and scope of my invention as pointed out in the appended claims.

Having thus described my invention, and illustrated its use, what I claim as new and desire to secure by Letters Patent, is the following:—

1. In a garment, the combination of a coat body member having a fixed collar piece and upper and lower back sections, and a transverse inclined back seam connecting the sections along a line intermediate the arm-holes and adjustable therealong whereby the material of the said sections may be conformed to the required contour across the shoulders without ripping off the collar piece, said coat body member being provided with substantially vertical seams disposed at the sides of the lower back section and each extending below one of the arm-holes to the bottom edge of the body member, said seam having a portion thereof capable of adjustment to maintain the alinement of the bottom edge of the back section upon adjustment of the back seam.

2. In a garment, the combination of a coat body member having a fixed collar piece and a back portion comprising upper and lower back sections, a transverse back seam connecting the sections, a side section connected at one marginal edge portion to both the back sections above and below said transverse seam, a front section, a substantially vertical seam connecting the front section to the other marginal edge of the side section, the said back sections being adjustable with reference to each other along the line of the transverse seam without ripping off the collar piece and the front and side

sections being similarly adjustable at the other seam, whereby to conform the material in the back portion of the body member upon adjustment of the back sections to the desired contour across the shoulders of the wearer.

3. In a garment of the character described, the combination of a coat body having a back portion comprising upper and lower back sections, a transverse inclined back seam adjustably connecting the back sections along a line intermediate the arm holes of the coat body, side sections extending in front of the arm holes and each connected at one marginal edge to the back sections above and below said transverse seam, front sections therefor, each adjustably connected to the other marginal edge of its adjacent side sections, and a collar piece fixedly connecting the top edge portions of the front and side sections and the upper back sections, substantially as and for the purpose set forth.

4. In a garment of the character described, the combination of a coat body member having a pair of upper and a pair of lower back sections; a back seam for connecting the upper pair of back sections to the lower pair along a downwardly directed V-shaped line extending intermediate the arm holes of said body member and adjustable therealong, a substantially vertical seam connecting the inner marginal edges of both pairs of sections and extending through the apex of said V-shaped back seam, said body member being provided with front portions adjustably connected with the outer side edges of one or more of the pairs of back sections below said V-shaped back seam; and a collar piece fixedly associated with said pair of upper back sections and said front sections, substantially as described.

In testimony whereof I have hereunto signed by name in the presence of the two subscribed witnesses.

JOHN ANTONELLI.
